UNITED STATES PATENT OFFICE.

ANDREW C. CAMPBELL, OF WATERBURY, CONNECTICUT, ASSIGNOR TO THE E. J. MANVILLE MACHINE COMPANY, OF WATERBURY, CONNECTICUT, A CORPORATION OF CONNECTICUT.

REVERSE-FEED FOR HEADING-MACHINES.

959,453.

Specification of Letters Patent. Patented May 31, 1910.

Application filed April 28, 1909. Serial No. 492,694.

To all whom it may concern:

Be it known that I, ANDREW C. CAMPBELL, a citizen of the United States, residing at Waterbury, in the county of New Haven 5 and State of Connecticut, have invented a new and useful Improvement in Reverse-Feeds for Heading-Machines, of which the following is a specification.

This invention relates to a mechanism for 10 feeding metal pieces or blanks to the die and punch of a heading, re-heading, trimming or similar metal swaging machine. This feed mechanism is designed to receive the blanks to be headed, re-headed, trimmed, or 15 otherwise shaped, from any ordinary form of delivery mechanism which presents the blanks, one by one, in a vertical position, and it carries the blanks thus received inwardly and downwardly, and at the same time turns 20 them in such manner that they are presented to the die, having the required configuration, in a horizontal position with their axes in line with the axis of the die opening and upsetting or swaging punch.

25 The object of this invention is to provide a mechanism for this purpose, which is simple to construct and operate, is very sure in action, and which can be easily set whenever desired by anyone, so that it will deliver the 30 blanks to the die with great accuracy, either end forward, in order that the desired end of the blanks may be operated upon by the punch.

Figure 1 of the accompanying drawings 35 shows a perspective view of a simple form of header provided with a feed which embodies this invention. As the heading mechanism forms no part of the present invention, only so much is illustrated as is necessary to a complete understanding of the relation of the feed to the other mechanisms. Fig. 2 shows a perspective view, on larger scale, of a portion of the frame of the machine, the end of a means for presenting the 40 blanks to the feed, and the feed mechanism which takes the blanks presented and delivers them axially in alinement with the die. Fig. 3 shows a plan, with parts in section, of the feed mechanism. Fig. 4 shows a side elevation of the same, with the feed fingers in their horizontal position. Fig. 5 shows a side elevation of the feed fingers in their 45 vertical position. The course of the blanks as they are carried by the fingers from the receiving position, shown in Fig. 4, to the

die position, shown in Fig. 5, is indicated in these figures. Fig. 6 shows a side view of the blank carrying fingers with the rotating mechanism arranged to turn the blanks the other end to, from the way they are turned 60 by the same mechanism arranged as shown in Figs. 3 and 4. Fig. 7 shows a plan, with parts in section, of a modified arrangement of the feeding mechanism. Fig. 8 shows a side elevation of this modification. 65

The frame 1, of the machine illustrated, near one end supports the transversely extending main shaft 2. This shaft at one end has the ordinary fly wheel 3, and between the sides of the frame has a crank 4. The 70 crank is connected by the pitman 5 with a gate 6, which is movable longitudinally on the ways 7 arranged along the insides of the sides of the frame. The gate carries a punch 8, which, when the machine is in 75 operation, is reciprocated toward and from the die 9 mounted in the end of the frame as usual in this class of machines. The die may have any necessary configuration to produce the desired pieces, and the punch 80 may be of any common form and construction necessary to act with the die to produce the desired result.

A bracket 10 is fastened to one side of the frame and supported by this bracket is the 85 end of the delivery trough 11, into which blanks 12 may be placed by hand, or by any suitable automatic mechanism. Mounted vertically in the bracket is a short rocker shaft 13. On the upper end of this rocker 90 shaft is a yoke 14, the ends of which are beveled so as to form an oblique passage 15 between them. On the lower end of the vertical rocker shaft is a rocker arm 16. This arm is, by a rod 17, connected with a lever 95 18, that is oscillated by a cam 19 on the main shaft. A spring 20 is arranged to draw the rod so as to hold the lever against the periphery of the cam. This mechanism, at the proper time, swings the yoke, first 100 one way and then the other way, so that its beveled ends pass between the first and second blanks, which are hanging vertically by their heads, at the end of the trough, and force the first outwardly into the fingers of 105 the feed mechanism, and at the same time hold the rest of the blanks in the trough (Figs. 3, 4).

In the first form of the invention illustrated, spring fingers 21 are fastened to an 110

arm 22 that is attached to the end of a shaft 23. This shaft extends through and is free to be rotated in a block 24 that is pivotally mounted on the upper end of a rocker 5 arm 25. This rocker arm projects from a rocker shaft 26, which is provided with a rocker arm 27, that, by a link 28, is connected with a rocker arm 29 on a shaft 30. The shaft 30 has a rocker arm 31, with a roll 10 32, that lies in the groove 33 of the cam block on the main shaft.

The shaft 23 has a spline groove 34, and splined upon this shaft is a sleeve 35, fastened to which is a gear 36. The sleeve 35 15 extends through and is rotarily held against longitudinal movement by a block 37 that is pivotally mounted at the top of the standard 38. In the form shown, the stem 39 of the block 37 passes through the hub 40 20 of a gear 41, that is held stationary in the top of the standard 38 by a set screw or any other means. The gears 36 and 41 intermesh, and as the gear 41 is stationary, when the shaft 23 is swung up and down the gear 25 36, which is oscillated with the shaft, is rotated so as to turn the shaft 23 on its longitudinal axis 90 degrees. The direction of rotation of this shaft for 90 degrees depends upon which side of the gear 41 that the gear 30 36 is located. When the shaft 23 is slid out of the sleeve 35, the gear 36 is free to be turned on the axis 39 of the block 37 so that it may be located on the right hand side of the gear 41, as shown in Figs. 3 and 4, or 35 on the left hand side of the gear 41, as shown in Fig. 6. After the gear 36 has been located on the proper side to give the desired turn to the shaft 23, that shaft is again passed through the sleeve 35.

40 When the rocker arm 25 stands vertical, the fingers are presented in front of the end of the trough in position to have the first or lowest blank forced into them by the oscillation of the yoke shaped gate 14. After 45 the fingers have received a blank, the rocker arm 25 is swung through an arc of 90 degrees, as indicated by the dotted line 42 on Fig. 4. This movement of the rocker arm first carries the fingers practically horizontal with the blank in a vertical position for a short distance, so the blank will clear the end of the trough. The continued movement of the arm then carries the fingers downwardly, the shaft 23 sliding through and being guided by the sleeve 35. As the shaft 23 50 with the fingers is carried down, the gear 36 rolling around the fixed gear 41, imparts to the shaft a rotation of 90 degrees on its axis. As the rocker arm 25 stops in a nearly horizontal position, the last part of the movement of the shaft and fingers is, for a short distance, practically vertical. This action carries the blank from the vertical position 55 at the end of the trough, shown in Fig. 4, to the horizontal position in axial alinement

with the die, shown in Fig. 5, on the course which is indicated by the dotted line 43, extending from one figure to the other. This organization, which carries the blank from a vertical position to a horizontal position at 90 degrees therefrom, at the same time turns the blank around 90 degrees so that it will align with the axis of the die opening and punch. As stated, by changing the position of the shaft gear 36 with relation to the fixed gear 41, the blank may be turned 90 degrees in either direction, and thus either end may be presented to the die, depending upon the operation to be performed. The same action can be accomplished in other 80 ways, for instance as shown in Figs. 7 and 8. In those figures, the shaft 44 provided with the spring fingers 45 which receive the blank 46 from the end of the race-way 47, extends through the sleeve 48 bearing a gear 49 in the same manner as before. The gear 49 is located to mesh with either side of a fixed gear 50, depending upon the direction of rotation to be given the shaft and spring fingers. In this case, the shaft is oscillated by 90 connecting a rocker arm 51 with the end of the stem 52 of the swivel block 53 that supports the sleeve 48 and the gear 49. The rocker arm may be connected by a rod 54 with any means for rocking it. This mechanism oscillates the shaft and spring fingers through an arc of 90 degrees, and at the same time rotates the shaft on its axis 90 degrees, so that the blanks may be taken from a vertical position and carried to a horizontal position, and either end presented to the die.

In order to guide the shaft and give the fingers a short retractive movement which is practically horizontal, after they have first 105 received the blank, and a short downward movement which is practically vertical, as they present the blank to the die, the shaft is provided with a grooved block 55, that is engaged by the segmental track 56, formed 110 on the edge of the rocker 57. This rocker is mounted on a rock shaft 58, and is provided with a rocker arm 59 that may be connected by a rod 60 with any means for rocking the parts. These mechanisms are so 115 timed that the segmental track draws the fingers and the blank approximately horizontally away from the end of the trough, just before the fingers are swung down. After the fingers and blank have been swung 120 down, the rocker is again turned so that the fingers will carry the blank down approximately vertically into accurate alinement with the die opening. By this organization the fingers are given a short reciprocation in 125 their upper position, so that they will move forward and grasp a blank, and then move back so that the blank will clear the runway when the fingers are swung down. It also gives the fingers a short reciprocation 130

when they are in their lowest position, so that the blank will be carried into line with the die opening, and then after the blank is grasped by the die, the fingers will rise and 5 free themselves from the blank and clear the punch and other mechanism, before they are swung up.

With both of the mechanisms described, the fingers approach the end of the trough, 10 and after grasping a blank move away without changing the vertical position of the blank, the purpose being to carry the blank safely out beyond the end of the trough before it is lowered. The mechanism also 15 makes it possible, whether the blank is presented one end or the other to the die, to raise and lower the blank for a short distance adjacent to the die in a practically horizontal position, in order that the blanks 20 may be properly presented to the die.

The invention claimed is:

1. A feed mechanism for a header, having fingers adapted to receive a blank, mechanism for swinging the fingers, and mechanism 25 for rotating the fingers on their longitudinal axis when they are swung.
2. A feed mechanism for a header, having fingers adapted to receive a blank, an oscillatory support for said fingers, a rotatory 30 guiding support for said fingers, and mechanism for rotating the fingers on their longitudinal axis as they are oscillated.
3. A feed mechanism for a header, having fingers adapted to receive a blank, an oscillatory support for said fingers, a swiveled 35 guide for said fingers, mechanism for oscillating the support, and mechanism for rotating the fingers on their longitudinal axis.
4. A feed mechanism for a header, having 40 fingers adapted to receive a blank, a rocker arm supporting said fingers, a pivotal connection between the rocker arm and said fingers, a swiveled block for guiding the fingers, mechanism for oscillating the rocker 45 arm, and mechanism for rotating the fingers on their longitudinal axis.
5. A feed mechanism for a header, having

fingers adapted to receive a blank, a rocker arm, a pivotal connection between the rocker arm and the fingers, a block for guiding the 50 fingers, a rotatory support for said block, mechanism for oscillating the rocker arm, and mechanism for rotating the fingers on their longitudinal axis.

6. A feed mechanism for a header, having 55 fingers adapted to receive a blank, a shaft supporting said fingers, mechanism for swinging the shaft on a transverse axis, and mechanism for rotating the shaft on its longitudinal axis as it is swung on its trans- 60 verse axis.

7. A feed mechanism for a header, having a rocker arm, mechanism for rocking the arm, a fixed support, fingers adapted to receive a blank, a pivoted connection between 65 said fingers and the rocker arm, a pivoted connection between the fingers and the fixed support, and mechanism for rotating the fingers on their longitudinal axis.

8. A feed mechanism for a header, having 70 fingers adapted to receive a blank, a shaft connected with the fingers, a gear splined upon said shaft, a fixed gear meshing with said splined gear, and means for swinging the shaft on a transverse axis. 75

9. A feed mechanism for a header, having fingers adapted to receive a blank, mechanism for swinging the fingers in a curved path, and mechanism for rotating the fingers on their longitudinal axis as they move 80 through the curved path.

10. A feed mechanism for a header, having fingers adapted to receive a blank, mechanism for reciprocating the fingers longitudinally at one time substantially horizontally, and at another time substantially vertically, and mechanism for swinging the fingers from a horizontal to a vertical position. 85
